GRINDING MACHINE

Lawrence B. Stogner, Hartsville, S. C., assignor
to Seneca Products Company, Hartsville, S. C.,
a Corporation of South Carolina

Application June 3, 1932. Serial No. 615,236

10 Claims. (Cl. 51—241)

This invention relates to grinding machines and more particularly to portable grinding machines of the type adapted to be applied to various kinds of apparatus for the purpose of grinding or abrading, *in situ*, certain elements thereof, the detachment or removal of which, for this purpose, would be impracticable.

The general object of the invention is to provide a novel and improved device of this character which is simple and compact in construction, easy to manipulate, and accurate in operation.

In its preferred embodiment, the invention contemplates the provision of a small portable machine provided with rotary abrasive members and a source of power for driving them, which machine is particularly adapted for application to the drawing rolls of a spinning frame.

As is well-known in the art, drawing rolls of the type commonly used in this connection are arranged in pairs, one of each pair disposed above the other, the lower ones being positively driven by means of suitable gearing and the upper ones generally being driven by frictional contact with the bottom rolls. The bottom rolls are made of steel and comprise a series of fluted portions each separated from the next adjacent portion by "necks" of less diameter than the fluted portions. These operative portions of the bottom rolls are fluted or longitudinally slotted for the purpose of aiding the bottom rolls in obtaining a better grip on the cotton as it passes between them and the top rolls. The top rolls are also of metal and are generally made in short lengths and assembled end to end. Those portions of the top rolls which lie adjacent the fluted portions of the bottom rolls are provided with cylindrical cork covered cots which are adapted to provide elastic surfaces of contact for the cotton fibers passing between the rolls. After continued operation of these drawing rolls, the cork surfaces of the top roll cots become worn by contact with the cotton and the fluted bottom rolls, and it is necessary to periodically grind or buff these cots in order to resurface them.

It is, therefore, a more particular object of the present invention to provide a portable power driven grinding machine which is well adapted to accomplish the resurfacing of these top roll cots and which comprises a novel clamping frame by means of which the device may be transported and may be temporarily secured to the bottom rolls of the spinning frame. The device also includes means for bringing the buffing or grinding element into contact with the surface of the top roll cots with the desired degree of pressure to effect the proper abrading action, and adjust-

able means for movably supporting a motor for driving the grinding elements.

Other objects and features of novelty will be apparent from the following specification when read in connection with the accompanying drawings in which one embodiment of my invention is illustrated by way of example.

In the drawings:

Figure 1 is a view in side elevation of a grinding device embodying the principles of my invention and showing the device applied to a pair of drawing rolls of a spinning frame, these rolls being shown in vertical cross-section;

Figure 2 is a plan view of my improved grinding device with the driving motor omitted;

Figure 3 is a transverse cross-sectional view taken on line 3—3 of Figure 1;

Figure 4 is a transverse cross-sectional view taken on line 4—4 of Figure 1;

Figure 5 is a longitudinal cross-sectional view taken on line 5—5 of Figure 2;

Figure 6 is a top plan view of the main frame of the grinding machine, portions of the pivoted frames thereof being shown in cross-section; and

Figure 7 is a fragmentary side elevation showing the grinding machine applied to a spinning frame and illustrating the manner in which the grinding wheel may be brought to bear upon any one of the upper rolls.

Referring particularly to Figure 1 of the drawings, the numeral 10 indicates the lower fluted roll of a pair of drawing rolls of a spinning frame. The corresponding upper roll is indicated at 11 and is provided with the cork covered cot 12. The section through the bottom roll 10 is taken at 90 one of the neck portions thereof which occur between the fluted sections which are adapted to contact with the top rolls. The section through the top roll, however, is taken at a point where the drawing action occurs, and the roll is shown 95 in contact with the buffing or grinding wheels 15.

The main frame of the grinding machine, together with its various adjustment features, is shown most clearly in Figure 6 of the drawings and is indicated generally by the letter A. The main frame A comprises essentially the combination of elements which will now be described. The rearwardly extending handle 20 is provided with bifurcations 21 which extend almost to the front end of the machine. A forward handle or bail 25 is adapted to straddle the front ends of the bifurcations 21 and is provided with downwardly and forwardly extending arms 26 which are secured to the members 21 by means of the connecting elements 27. The lower ends 110

of these arms 26 extend forwardly in a direction parallel to the members 21 and are provided with openings for the reception of the forward cross rod 28. A rear cross rod 29 also passes 5 through openings in the members 21 as at 30. Two outer frame members 31 and 32 are mounted on the cross rods 28 and 29 for lateral adjustment and at their forward ends are provided with jaws 33 and 34 which are adapted to receive the bottom rolls 10 as shown in Figures 1 and 5 of the 10 drawings.

The lateral adjustment of these side frame jaw members 31 and 32 is accomplished by means of the rotatable cross bolt 35, the ends of which 15 are provided with threads of opposite hand. The bolt 35 is provided at its mid-portion with the knurled wheel 36, the hub portion 37 of which is adapted to rotate between the arms 21 of the handle portion 20 of the main frame. It will 20 be readily understood that rotation of the shaft 35 in one direction will cause the lower jaw members 33 and 34 to approach each other and that rotation in the opposite direction will cause them to recede. This adjustment permits the application 25 of the device to bottom rolls, the fluted portions of which may be of varying lengths.

A pivoted upper jaw member 40 is fulcrumed upon the cross rod 28, and its rearwardly extending shank 41 is positioned below the main 30 frame and has its rear end secured to an upwardly directed actuating lever 42 as at 43. The shank 41 is bifurcated, as shown in Figure 3, in order to receive the lower portion of the lever 42 and the extension 44. A coil spring 45 is adapted 35 to connect the portion 44 with a cross pin 46 which extends between the elements 21 of the main frame. It will be readily seen that the spring 45 continually urges the lower jaws 33 and 34 and the upper jaw 40 toward each other 40 so as to firmly grip the bottom roll 10. This clamping arrangement may readily be released by a downward pressure on the end portion 47 of the handle 42.

A movable frame B is pivoted to the main 45 frame A and is adapted to support the abrading wheels 15 and to be manipulated so as to bring these abrading members into the desired contact with the cots 12 on the top rolls 11. The frame B comprises essentially the side bars 50 and 51 which are pivotally secured to the outer main frame members 31 and 32 as by means of the 50 bolts 52 and 53. The upwardly and forwardly projecting ends of these bars 50 and 51 are provided with adjustable extensions 54 and 55 which 55 are adapted to carry the bearings 56 and 57 within which is received the axle 59 of the grinding wheels 15. These forward extensions 54 and 55 are fulcrumed upon the bolts 60 and 61 which are secured to the side bars 50 and 51 respectively.

The rear ends of the members 54 and 55 are turned upwardly and inwardly so as to overlie the upper edges of their associated members 50 and 51, as clearly shown at 63 and 64. Set screws 66 and 67 are threaded through the inwardly extending portions of the members 54 and 55, and their lower ends are adapted to bear upon the top edges of the bars 50 and 51. These set screws are provided with knurled heads for aiding in rotating them, and the knurled lock nuts 68 and 69 are adapted to secure the set screws in their 65 adjusted positions. A spring 70 is adapted to urge the rear ends of the members 54 and 55 downwardly and thus urge the adjacent end of the axle 59 upwardly. This tendency may be 70 counteracted by the proper adjustment of either

of the set screws 66 or 67, and by this means the proper level or parallel position of the grinding wheels 15 may be obtained.

The rear portions of the bars 50 and 51 of the pivoted grinding wheel carrying frame B are adapted to extend below the main frame and terminate in the return bent portions 72 and 73. Both the main rear portion of the bars 50 and 51 and these return bent portions 72 and 73 are provided with openings to receive the cross bar 75. Outwardly of the side frame members 31 and 32, there are positioned on the rear cross shaft 29 the sleeves 77 and 78 which may be secured to these members 31 and 32 and which provide stops or abutments for the rear portions of the bars 50 and 51 of the pivoted wheel carrying frame.

An operating handle or lever 80 is provided with forwardly extending bifurcated portions 81 and 82, the forward ends of which are provided with openings through which is adapted to extend the rear cross rod 29 of the main frame. Intermediate the ends of this bifurcated lever 80 is pivotally suspended the U-shaped link 85 as by means of the bolts 86 and 87. The arms of the link 85 near the bottom portion of the link are provided with openings through which the central portion of the cross bolt 75 is adapted to be received. This provides a pivotal connection between the operating handle 80 and the pivoted grinding wheel carrying frame B.

The arrangement for supporting the driving means for the grinding wheels 15 will now be described. A motor carrying frame C is provided which comprises a vertically extending bracket 90 to which is suitably secured the motor 91 having a vertically disposed armature shaft 92, upon the lower end of which is fixed the pulley 93 about which passes the belt 95 which extends forwardly of the apparatus and around the pulley 96 which is secured to the axle 59 of the grinding wheels 15. The lower portion of the motor supporting frame C comprises the two spaced arms 98 and 99 which are pivotally connected to the arms 21 of the main frame handle 20 as at 100 and 101.

It is obvious that the motor carrying frame C must partake of substantially the same movements as the grinding wheel supporting frame B in order to maintain the operative driving connections, and the following adjustable means is provided for maintaining this relationship. A yoke 105 having a central downwardly depending portion 106 is pivoted at its ends to the members 98 and 99 of the motor carrying frame C. The portion 106 is provided with an opening which is adapted to receive the bolt 107, the lower end of which is provided with the sleeve portion 108 adapted to receive the shaft 75 which forms the part of the connection between the pivoted frame B and the actuating handle 80. A nut 109 is threaded upon the bolt 107 above the yoke 105, and by rotating this nut, the proper relative positions of the frames B and C may be obtained. A coil spring 110 surrounds the shank of the bolt 107 and is adapted to be compressed between the depending central portion 106 of the yoke 105 and the sleeve portion 108 of the bolt 107. In practice, after the belt 95 has been applied to the pulleys 93 and 96, the nut 109 is rotated to a position to apply the proper tension to the belt 95, and the coil spring 110 provides the necessary resilience in preventing undue strain upon the belt during operation.

A bolt 112 is threaded through the handle 20 of the main frame A, and the lower end thereof

is adapted to provide a stop or abutment for the handle 80 in order to limit the downward movement of the grinding wheel 15.

The application and operation of the device will be readily understood. The machine should be grasped by the forward bail handle 25 with one hand, and the levers 20 and 80 are gripped with the other hand. In order to open the clamping members of the main frame, the handle 42 is depressed by applying pressure with the thumb to the upper end 47 thereof. This, of course, will raise the upper jaw member 40 and permit the application of the lower jaws 33 and 34 to the neck portions of the bottom rolls 10. Upon release of the handle 42, 47, the upper jaw 40 will come into gripping contact with the bottom rolls either at a neck portion thereof or against the fluted portion itself. The machine is now temporarily attached to the spinning frame for operation. Next, the grinding wheels 15 are adjusted so that their axle 59 is parallel with the axis of the top rolls 11, by means of the set screws 66 and 67. Then the grinding wheels 15 are brought into proper contact with the surfaces of the top rolls by an upward movement of the lever 80. The motor 91, which is adapted to receive its current from a suitable source, is then started, and the abrading or resurfacing operation may be readily effected.

Figure 7 illustrates clearly the application of the grinding machine to a spinning frame, whereby not only the first upper roll cots may be resurfaced but also those of the other upper rolls of the series. The first lower roll is retained as the pivotal clamping point for the machine, and the machine is raised about this pivot at the same time that the grinding wheels are moved upwardly about their pivots 53. It will thus be seen that the wheels 15 are extended over the nearer rollers in order to contact with those at the rear portion of the frame by suitable manipulation of the handles 20 and 80.

By means of the mechanism already described, the main frame may be adjusted laterally to accommodate the attaching jaws thereof to the particular bottom rolls to which the device is to be applied by means of the rotatable shaft 35 which is actuated by the wheel 36. The proper belt tension can also be obtained by the adjustment of the connecting mechanism 105-110.

It will also be readily understood that various changes and modifications can be made in the embodiment illustrated and described herein without departing from the scope of the invention as defined in the following claims.

Having thus described the invention, what is claimed as new and desired to be secured by Letters Patent is:—

1. A portable device of the type adapted to be attached to a machine for the purpose of grinding or resurfacing an element thereof, said device comprising a main frame, a pivotally mounted frame carried by said main frame, a grinding member on said pivotally mounted frame, another pivotally mounted frame carried by said main frame, a motor mounted on said second named pivot frame, a belt operatively connecting said motor with said grinding member, a manually operable lever for moving said pivotally mounted frames to apply said grinding member to the element to be abraded, and an adjustable connection between the two pivotally mounted frames for regulating the relative positions thereof and thus the tension in said belt.

2. A portable device of the type adapted to be

attached to a machine for the purpose of grinding or resurfacing an element thereof, said device comprising a laterally expandable main frame, means for effecting expansion and contraction thereof, clamping jaws associated with said main frame for attaching the device to a portion of said machine, a manually operable lever for actuating said jaws, a pivoted frame carried by said main frame, a rotary grinding wheel supported by said pivoted frame, a manually operable lever for moving said pivoted frame whereby said grinding wheel may be brought into the desired contact with said element to be resurfaced, means for adjusting the alignment of said rotary grinding wheel with respect to said element, another pivoted frame carried by said main frame, a motor disposed upon said second named pivoted frame, a belt operatively connecting said motor with said grinding wheel, and means for resiliently adjusting the relative positions of said movable frames for movement in unison and for regulating the tension in said belt.

3. A portable grinding machine for resurfacing the top drawing rolls of spinning frames comprising, in combination, a main frame, a rearwardly extending handle for said main frame, a supplemental frame pivoted to said main frame, a grinding device mounted on said supplemental frame, and a manually operable lever for moving said supplemental frame to apply the grinding device to the rolls, the manipulative portion of said lever being disposed adjacent said handle and cooperating therewith to provide means for grasping said machine during operation thereof.

4. A portable grinding machine for resurfacing the top drawing rolls of spinning frames comprising, in combination, a main frame, a rearwardly extending handle for said main frame, a supplemental frame pivoted to said main frame, a grinding device mounted on said supplemental frame, a manually operable lever for moving said supplemental frame to apply the grinding device to the rolls, the manipulative portion of said lever being disposed adjacent said handle and cooperating therewith to provide means for grasping said machine during operation thereof, and a pincer-like clamping device on said main frame for applying the machine to the bottom rolls of said spinning frame.

5. A portable grinding machine for resurfacing the top drawing rolls of spinning frames comprising, in combination, a main frame, a rearwardly extending handle for said main frame, a grinding tool on said main frame, and a manually operable pincer-like clamp adapted to seize the necks of one of the bottom rolls of the spinning frame for supporting the machine in grinding position.

6. A portable grinding machine for resurfacing the top drawing rolls of spinning frames, comprising, in combination, a main frame, a rearwardly extending handle for said main frame, a supplemental frame pivoted to said main frame, a grinding device mounted on said supplemental frame, a manually operable lever for moving said supplemental frame to apply the grinding device to the rolls, the manipulative portion of said lever being disposed adjacent said handle and cooperating therewith to provide means for grasping said machine during operation thereof, and an adjustable stop on said handle adapted to be contacted by said lever for regulating the extent of movement of said supplemental frame.

7. A portable grinding machine for resurfacing the top drawing rolls of spinning frames comprising,

ing, in combination, a substantially rectangular, laterally expandible main frame, a rearwardly extending handle for said main frame, a supplemental frame pivoted to said main frame, a grinding device mounted on said supplemental frame, and a manually operable lever for moving said supplemental frame to apply the grinding device to the rolls, the manipulative portion of said lever being disposed adjacent said handle and 10 cooperating therewith to provide means for grasping said machine during operation thereof.

8. A portable grinding machine for resurfacing drawing roll cots comprising, in combination, a substantially rectangular main frame 15 which includes a longitudinal center bar, a pair of laterally spaced side bars, transverse rods connecting said bars, clamping jaws formed on said side bars for receiving the necks of a bottom roll of a drawing frame for supporting said machine in operative position, a cooperating clamping jaw pivoted to said center bar, a handle on said center bar, means for adjusting said side bars laterally to expand said frame to fit bottom rolls of various contours, a supplemental frame 25 attached to said main frame, and a grinding wheel mounted on said supplemental frame.

9. A portable grinding machine for resurfacing drawing roll cots comprising, in combination, a substantially rectangular main frame which 30 includes a longitudinal center bar, a pair of laterally spaced side bars, transverse rods connecting said bars, clamping jaws formed on said side bars for receiving the necks of a bottom roll of a drawing frame for supporting said machine 35 in operative position, a cooperating clamping jaw pivoted to said center bar, a handle on said center bar, means for adjusting said side bars laterally to expand said frame to fit bottom rolls of various contours, a supplemental frame pivoted 40

intermediate its length to said main frame, a grinding wheel mounted upon one end of said supplemental frame, a lever pivoted to said main frame and extending adjacent said handle, and a link connecting said lever and said supplemental 80 frame whereby relative movement of said lever and said handle is adapted to effect the adjustment of the grinding wheel with relation to said cots.

10. A portable grinding machine for resurfacing drawing roll cots comprising, in combination, a substantially rectangular main frame which includes a longitudinal center bar, a pair of laterally spaced side bars, transverse rods connecting said bars, clamping jaws formed on said side 90 bars for receiving the necks of a bottom roll of a drawing frame for supporting said machine in operative position, a cooperating clamping jaw pivoted to said center bar, a handle on said center bar, means for adjusting said side bars laterally to expand said frame to fit bottom rolls of various contours, a supplemental frame pivoted intermediate its length to said main frame, a grinding wheel mounted upon one end of said supplemental frame, a lever pivoted to said main 100 frame and extending adjacent said handle, a link connecting said lever and said supplemental frame whereby relative movement of said lever and said handle is adapted to effect the adjustment of the grinding wheel with relation to said 105 cots, a second supplemental frame pivoted to said main frame, a motor mounted on said second supplemental frame and operatively connected with said grinding wheel, and a link connecting said second supplemental frame with said lever whereby manipulation of said lever will serve to effect the adjustment of said motor carrying frame simultaneously with said grinding wheel frame.
